UNITED STATES PATENT OFFICE

152,226

DESIGN FOR A SCROLL SAW

Clifford Brooks Stevens, Milwaukee, Wis., assignor to Rockwell Manufacturing Company, Pittsburgh, Pa., a corporation of Pennsylvania

Application August 15, 1947, Serial No. 140,899

Term of patent 14 years

(Cl. D93—3)

To all whom it may concern:

Be it known that I, Clifford Brooks Stevens, a citizen of the United States, residing in Milwaukee, in the county of Milwaukee and State of Wisconsin, have invented a new, original, and ornamental Design for Scroll Saw, of which the following is a specification, reference being had to the accompanying drawing, forming a part thereof.

I claim:

The ornamental design for a scroll saw, substantially as shown.

CLIFFORD BROOKS STEVENS.
